DESIGN FOR A FLAG OR SIMILAR ARTICLE

Sydney D. Mahan, Washington, D. C., assignor to the United States of America, as represented by Henry Morgenthau, Jr., Secretary of the Treasury, and his successors in office

Application May 16, 1942, Serial No. 106,922

Term of patent 7 years

To all whom it may concern:

Be it known that I, Sydney D. Mahan, a citizen of the United States, residing at 1314 Massachusetts Avenue Northwest, Washington, District of Columbia, have invented a new, original, and ornamental Design for a Flag or Similar Article, of which the following is a specification, reference being had to the accompanying drawing, forming a part thereof.

The figure is a plan view of a flag, showing my new design.

While I have shown my design in the form of a flag, it is understood that the design may be placed on similar articles such as banners, buttons, without departing from the spirit of my invention.

I claim:

The ornamental design for a flag or similar article, as shown and described.

SYDNEY D. MAHAN.
